UNITED STATES PATENT OFFICE.

EARLE C. POWERS, OF STRATFORD, NEW JERSEY, ASSIGNOR TO B. F. STURTEVANT COMPANY, OF BOSTON, MASSACHUSETTS, A CORPORATION OF MASSACHUSETTS.

HOSIERY DRIER.

Application filed April 12, 1922. Serial No. 552,014.

To all whom it may concern:

Be it known that I, EARLE C. POWERS, a citizen of the United States, residing at Union Ave., Stratford, in the county of 5 Camden and State of New Jersey, have invented certain new and useful Improvements in Hosiery Driers; and I do hereby declare the following to be a full, clear, and exact description of the invention, such 10 as will enable others skilled in the art to which it appertains to make and use the same.

This invention relates to drying apparatus and more particularly to apparatus for drying 15 hosiery.

The object of the invention is to provide 20 drying apparatus of novel and improved construction adapted primarily for drying hosiery in an improved and superior manner, although certain features of the invention may be used with advantage in apparatus for drying other material.

With this object in view the invention 25 consists in the drying apparatus herein-after described and particularly defined in the claims.

In the drawing illustrating the preferred embodiment of the invention, Figure 1 is 30 a vertical section of the improved drying apparatus; Fig. 2 is a plan with a portion broken away; Fig. 3 is an end elevation with a portion broken away; Figs. 4, 5 and 6, are details of the stocking support and tray to be referred to, and Fig. 7 is a detail 35 of the door catch.

The illustrated dryer comprises, in general, a box or chamber having the upper portion of its interior sub-divided into a 40 number of drying compartments within which the stockings to be dried which have previously been drawn over thin wooden forms are supported side-by-side upon their edges in suitable trays. Fans are provided, one for each compartment, for rapidly circulating 45 a current of air over the stockings and through the drying compartments to accomplish the drying operation. A heating compartment is located in the lower portion of the chamber, and the temperature of the 50 circulated air is carefully controlled in an automatic manner to maintain it relatively low, i. e. well below the boiling point of water, so that the material of the hosiery may not be injured during the drying opera-

tion. The circulation of the air is maintained at a relatively high velocity so that the drying operation may be accomplished and completed within a period of time conducive to the economic drying of the hosiery and without interfering with the commercial 55 quantity production of hosiery as now practiced in knitting mills. An exhaust flue is connected with the interior of the chamber, for the purpose of removing a portion of the air from the chamber whenever a compartment door is opened and of causing an 60 indraft of fresh air. Dampers, automatically controlled by the compartment doors, cut off the circulation through the compartments, thus preventing the outflow of hot 65 moist air into the face of the operator and into the room when the doors are opened.

Referring to the drawings, the illustrated 70 drier comprises a chamber 10 formed by a steel frame 12, having insulated sides 14 and top 16 secured thereto. The upper portion of the interior of the chamber 10 is subdivided into three drying compartments formed by inverted U-shaped sheet metal forms 15 located side-by-side. The sheet 75 metal forms 15 are supported upon cross-bars 20, secured to the frame 12, and the bottoms of the drying compartments are formed by the top surface of an exhaust duct 22 extending transversely across the 80 chamber 10, as shown in Figs. 1 and 3, and communicating through an outlet pipe 24 with the flue leading to the exhaust fan 85 furnished as part of the drying equipment. The forward end of the exhaust duct 22 is 90 open as shown at 26 across the entire width of the chamber 10. Between the forward end of the top surface of the exhaust duct and the front wall of the drier is a space or opening 95 25 through which the air passes from the drying compartments down into the common heating chamber 27 formed by the space below the exhaust duct.

In order to cause circulation of the air 100 through the drying compartments, each compartment is provided with its individual fan 30 mounted upon the end of a driving shaft 31 journaled in a bearing 32 upon the forward end of an angle support 34. The fan shaft 31 is extended to without the 105 chamber 10 and is operatively connected with a motor 37 supported upon the outer end of the angle support, as shown in Fig.

1. Each of the fans 30 draws air from the common heating chambers 27 through suction or supply chambers 40 in the rear of the fans, which are separated from one another by the vertical partitions 41, as shown. The circulation of the air through the drying compartments is controlled by means of dampers 42 pivotally supported upon the rear wall of the drier, one for each of the 10 drying compartments. When the dampers are raised into the position illustrated in full lines in Fig. 1, the circulation of air from the common heating chamber 27 to the particular fan is cut off, thereby cutting 15 off further circulation by the fan through the drying compartment.

In order to converge the air current as it leaves the fan and to direct it upon the heel and toe portion of the stockings, deflectors 20 43 are provided which are preferably formed of sheet metal in the form of a frustum of a four-sided pyramid arranged with the smaller ends secured to and forming a continuation of the walls of the individual 25 drying compartments. The larger ends of the deflectors 43 are secured to a transverse partition 44 extending across the upper portion of the chamber 10, being secured to the side walls thereof. The plate is provided 30 with circular openings for the fans 30. The top and bottom walls of each deflector are secured to the plate 44, as shown in Fig. 1, the bottom wall being bent under the lower edge of the plate so as to form an abutment 35 for the damper. The vertical sides of the deflectors are formed, as shown in Fig. 2, being secured to the plate 44 by rivets or otherwise.

Each compartment is arranged to hold 40 one dozen stockings, each of which has been drawn over a thin wooden form. These are supported edgewise on a movable tray which may be partially withdrawn from the drying compartment through the door to 45 permit the replacing of the dried stockings by others to be dried.

Mounted upon the guides 45 are the trays 47 which comprise an open rectangular frame formed by the side bars 48, held in 50 parallel relation to one another by cross-bars 49. The trays 47 are provided at their rear end with a pair of rollers 50 secured to the bars 48, as shown in Fig. 5. The forward end of the trays rest on stationary rollers 55 50 as shown in detail in Fig. 6.

The front cross-bar 49 is provided with a series of upstanding guides 51 spaced apart for the reception of the boarded stockings between adjacent guides. The guides 51 are 60 preferably formed as shown in Fig. 3, and comprise inverted U-shaped wires, the free ends of which are secured in the cross-bar 49. A strip of flexible resilient material 52 such as felt is woven in and out through the 65 guides serving as a resilient support for the

boarded stockings. A handle 53 secured to the cross-bar 49 enables the operator to withdraw conveniently the frame from the drying compartment into its extended position.

The foot portions of the boarded stockings are supported upon a combined heel and toe rest 55 illustrated in detail in Figs. 4 and 5, comprising two glass rods 57. The ends of these rods are removably received in slots 58 in upright members 59 which are 70 rigidly connected by side arms 61 to maintain the glass rods in fixed relation to one another, and by the cross supports 62, to form a rigid structure which is capable of being adjustably moved as a unit with relation to the tray to compensate for variations in the length of the boarded stockings. This adjustment is secured by a series of notches or recesses 64 formed in the upper portion of the side bars 48 of the tray 47 75 and in which lugs 65 depending from the rear members 59 of the heel and toe rest are received. When it is desired to adjust the position of the heel and toe rest with relation to the tray, the end of the rest is lifted 80 bodily, withdrawing the lugs from cooperation with the recesses and thereby permitting the rest as a unit to be adjusted to the desired position.

A U-shaped stop 66 is provided in each 85 drying compartment with which the front and rear cross-bars 47 of each tray cooperate to limit the rearward and forward movement of the trays 47 in the guides 45.

In order that the circulation of air 100 through an individual drying compartment may be cut off whenever its door 70 is opened, the latter is operatively connected with the damper 42. In normal operations, when the door stands closed, the damper is 105 in the dotted line position, Fig. 1, thus establishing a closed cycle for the circulation of air from the fan 30 through the drying compartment down through the opening or passage 25, into the heating chamber and 110 thence upwardly over the damper 42 to the suction chamber 40 immediately in the rear of the fan. When the door 70 is opened, this balanced system of circulation is 115 destroyed by cutting off, by means of the damper, the air supply to the suction chamber from the common heating chamber. This is accomplished by means of a link 72 connected to one arm 73 of a bell crank 74 pivoted upon the support or guide for the 120 stocking tray, the second arm 75 of the bell crank being connected by a link 76 to a lug 78 upon the inside surface of the door. From inspection of Fig. 1, it will be apparent that when the door is closed, the 125 damper 42 is swung down into the dotted line position, and that when the door is opened, the damper is swung into the full line position shown in Fig. 1, effectively cutting off the suction side of the fan from 130

the heating chamber. Furthermore, whenever a door is opened some of the moist air is drawn out through the exhaust duct in which a suction is continuously maintained, and a fresh supply of air is automatically drawn in through the open door. In order to prevent the fresh air incoming through the open door from passing into and mixing directly with the circulating air in the next drying compartment, vertical partitions 79 are provided in the forward part of the heating chamber 27. To prevent leakage of air from the interior of the drier the doors 70 are provided with bevelled surfaces 71 adapted to cooperate with correspondingly bevelled surfaces on the face of the door openings in the front of the drier. After the door is shut, the operator pushes down upon the handle 77, pivoted at 82, see Fig. 7, and the upward movement of the inner end of the handle operates to raise a movable latch member 84 into engagement with a wedge 85 to cause the door to be drawn inwardly and locked. A rubber gasket 91 assists in providing an air tight joint at the top of the door.

The drying air is heated by means of a series of heating coils 80 extending transversely across the entire width of the heating chamber 27, as shown in Figs. 1 and 2. These heating coils run into headers 81 at each end and the flow of steam to the coils is controlled by a thermostatically operated valve 821 located in the steam inlet pipe 83 leading to the coils, a portion of which is shown in Figs. 1 and 2. The thermostatic element 841 for the thermostatically controlled valve 821 is located in the path traversed by the air as it is withdrawn from the common heating chamber 27 and circulated through one or more of the drying compartments. In order to compensate for any variations in the temperature of the air when one of the doors in the drying compartments is opened, the thermostatic element is preferably arranged to extend from the middle suction chamber 40 to one of the end chambers and through the dividing partition 41 between them. The thermostatic element is conveniently supported upon the angle supports, as shown in Figs. 1 and 2. The details of construction and mode of operation of the thermostatic valve may be of any desired or approved form and which are well known and of themselves comprise no feature of the present invention. The thermostatically operated valve 821 is provided with the usual adjustment by which the operation of the valve may be controlled to admit sufficient steam or other heat containing liquid to the heating coils to maintain the temperature of the air in the heating chamber 27 and the drying compartments within predetermined limits.

In drying silk hosiery the practice here-

tofore has been to heat the circulating air to as high a temperature as could be conveniently secured with the steam pressures available in the ordinary drying room. These temperatures amounted to approximately from 220 to 300 degrees F. and were necessary in order that the required production from the drying apparatus might be obtained. With the ordinary type of high temperature drier, the rate of drying approximated a dozen stockings within a period of 6 to 8 minutes. Because of the fact that the fibres thereof contain volatile constituents including the natural oils, the exposure to the excessively high temperatures has resulted in the loss of some of these natural volatile constituents from the fibres during the drying operation. The formation of the well-known blue haze so common to drying rooms at the present time bears out the assertion that these oils are lost or at least decomposed during the drying operation. In addition, deleterious effects are produced in the organic dyes by the baking at the high temperatures. It is therefore highly important that in the drying of hosiery, particularly silk hosiery, and for other material, that provision be made for definitely and accurately controlling the temperatures of the circulating air so that they may be maintained well below the critical temperature at which injury to the stockings takes place. In practice, I have found with a certain quality of silk hosiery now being put upon the market, excellent results may be secured by maintaining the temperature around 125 degrees F. and circulating the air at approximately 1000 feet per minute, delivering the air directly upon the stockings. With air of this temperature and velocity 6 to 8 minutes is required for drying.

In the use of the drier, the stockings, as they come from the bleaching and drying operations are laid upon the upper or top surface of the drier. The height of the drier is intentionally made in the neighborhood of 3½ feet so as to afford a convenient boarding or working table for an operator. The latter stands in front of the drier and boards the stockings upon the wooden forms in the usual manner in lots of a dozen each. The operator is provided with four sets of forms, so that there may always be one set available for boarding, while the other three sets are in the drier. After each lot of stockings have been boarded, a compartment door is opened and the tray withdrawn. The opening of the door automatically cuts off the circulation of air from that particular compartment, and at the same time some of the moist air is withdrawn through the exhaust duct and fresh air drawn in through the open door. The stockings are placed in the tray, being arranged edgewise and side

by side, the upper ends of the boarded stockings being received between the up-standing guides and the foot portion of the stocking being supported by the two glass rods of the combined heel and toe rest. The tray is then pushed into the interior of the drying compartment and as the door is closed the damper is swung into the dotted line position, Fig. 1, thereby automatically 10 starting the circulation through the drying compartment.

The relatively high velocity of the air breaks up the surface films of the moisture in the hosiery and enables the air to penetrate the interstices of the knitted material thereby removing the moisture from both the surface and the interior of the fabric. By converging the air as it is delivered from the fan upon the toe and heel portions of the 20 stockings, the drying of these portions is greatly facilitated. This is a feature of importance because, owing to the greater weight or thickness of these parts, they are more difficult to dry. Furthermore, since 25 the air flows at a relatively high velocity from the foot towards the top of the stocking, the formation of wrinkles such as commonly occurred in the use of driers of the prior art is avoided and a superior finish imparted to the goods without the necessity of paper pressing.

The top surface of the drier being arranged at a height convenient for the boarding of the stockings thereon enables the efficiency of the operator to be greatly increased, not only because of the time saved in eliminating the necessity of walking from a separate boarding table to the drier, but also in reducing fatigue and unnecessary effort on the part of the operator. The top and side walls of the drier are preferably formed of insulating material, which together with the fact that the drying operation itself is carried on at a relatively low 40 temperature and without the escape of the hot moist air from the drier whenever stockings are removed from or placed therein, eliminates the uncomfortably high temperature and disagreeable working conditions 45 usually found in present day hosiery boarding room.

While the preferred embodiment of the invention has been illustrated and described, it is to be understood that the invention may 50 be embodied in other forms within the scope of the following claims.

Having described the invention what is claimed is:

1. A drying apparatus comprising a 60 chamber, a plurality of separate drying compartments in communication with the chamber, fans, one for each drying compartment, for circulating the air through the chamber and through the individual drying compartments and means bodily and independently

removable from the drying compartments for supporting the material to be dried within each drying compartment.

2. A drying apparatus comprising a chamber, a plurality of separate drying compartments arranged side by side within the chamber, a heating compartment extending along the drying compartments, fans, one for each drying compartment, for circulating air from the heating compartment through the 70 individual drying compartments, and means for supporting the material to be dried in each drying compartment.

3. A drying apparatus comprising a chamber, a plurality of drying compartments arranged within the upper part of the chamber, a heating compartment formed below the drying compartments, means for circulating air from the heating compartment through the individual drying compartments, and dampers controlling the circulation of air through each drying compartment.

4. A drying apparatus comprising a drying compartment, a door for the drying compartment, means for circulating air through the drying compartment and towards the door, and devices controlled by the door for controlling the circulation of air through the drying compartment.

5. A drying apparatus comprising a plurality of separate drying compartments, means for circulating air through the drying compartments, doors leading to each drying compartment, and dampers for controlling the circulation of air to each drying compartment operatively connected with the doors to cut off the circulation through a drying compartment when its door is open.

6. A drying apparatus comprising a drying compartment, means for circulating air through the drying compartment, devices for controlling the circulation of air through the drying compartment, a door leading to the drying compartment, and connections 100 between the devices and the door for stopping the circulation of air when the door is opened.

7. A drying apparatus comprising a chamber, a plurality of drying compartments arranged in the upper part of the chamber, a heating chamber formed below the drying compartments, dampers for each drying compartment controlling the circulation of air therethrough, doors leading to each drying compartment, connections between each door and the corresponding damper for closing the damper when the door is open.

8. A drying apparatus comprising a drying compartment, a door for the drying compartment, and means normally inoperative when the door is closed for exhausting air from the compartment when the door is opened.

9. A drying apparatus comprising a normally closed chamber, means including an exhaust flue normally in communication with the interior of the chamber and tending to exhaust air therefrom, and a door for the chamber which when opened permits exhaustion of air from the chamber and the admission of a supply of fresh air.
10. A drying apparatus comprising an enclosed chamber having a drying compartment, means including an exhaust flue in open communication with the interior of said chamber for exhausting air therefrom, means for circulating air within the chamber and through the drying compartment, and a door for the compartment, said door controlling the air circulating means and when opened cutting off the circulation through the compartment and permitting the exhaustion of air from the chamber and the admission of fresh air.
11. A drying apparatus comprising a chamber, a plurality of separate drying compartments within the chamber, a heating compartment within the chamber, means for circulating air in a closed cycle from the heating compartment through each drying compartment, and devices for cutting off the circulation of air through the individual drying compartments and for exhausting a portion of the moist air therefrom.
12. A drying apparatus comprising a chamber, a plurality of separate drying compartments within the chamber, a heating compartment within the chamber, means for circulating air in a closed cycle from the heating compartment through each drying compartment, and devices for cutting off the circulation of air through the individual drying compartments and at the same time for exhausting a portion of the moist air therefrom and for admitting a supply of fresh air thereto.
13. A drying apparatus comprising a chamber, a plurality of drying compartments arranged within the upper part of the interior of the chamber, heating coils arranged below the drying compartments, fans at the rear portion of the interior of the chamber for circulating air through the individual drying compartments, and dampers controlling the circulation of air through each drying compartment.
14. A hosiery drier comprising a chamber, a series of drying compartments arranged in the upper portion of the interior of the chamber, stocking trays in each drying compartment, doors leading into the forward end of each drying compartment, a series of heating coils below the drying compartments, individual fans for each drying compartment, dampers controlling the circulation of air from the heating chamber to the suction side of the fans, and connections between the dampers and doors for closing the dampers when the doors are opened.
15. A hosiery drier comprising a chamber, a plurality of drying compartments arranged side by side in the upper portion of the chamber, an exhaust duct extended transversely across the interior of the chamber below the drying compartment, the upper surface of the top of the duct forming the bottom of the drying compartments, a passageway between the forward end of the exhaust duct and the front of the drier, heating coils spaced below the exhaust duct, fans at the rear ends of the drying compartments, dampers for each fan controlling the passage of air from the heating chamber to the fan, and a valve thermostatically operated by the temperature within the chamber for controlling the supply of heat to the heating coils.
16. A hosiery drier comprising a chamber, a plurality of separate drying compartments within the chamber, a fan for each drying compartment, a heating compartment within the chamber in communication with both ends of each of the drying compartments, and dampers controlling the circulation of the air from the heating chamber through each drying compartment.
17. A hosiery drier comprising a chamber, a plurality of separate drying compartments within the chamber, a common heating compartment means located between the drying and heating compartments for circulating heated air through the drying compartments, means for exhausting the moist air from within the chamber, and means for independently controlling the circulation of air through each compartment.
18. A hosiery drier comprising a chamber, a plurality of drying compartments arranged side by side in the upper portion of the chamber, a heating compartment formed below the drying compartments, the chamber having connecting passages between the heating compartment and each end of the drying compartments, and means for circulating heated air in cycles from the heating compartment through each drying compartment.
19. A hosiery drier comprising a chamber, a plurality of drying compartments arranged side by side in the upper portion of the chamber, doors leading to each drying compartment, a heating compartment formed below the drying compartments, the chamber having passages connecting the heating compartment with each end of the drying compartments, dampers in one of said passages, and connections between the dampers and the doors for cutting off the circulation when the door is opened.
20. A hosiery drier comprising a chamber, a drying compartment within the cham-

ber, devices for supporting a plurality of boarded stockings within the drying compartment, and a fan for circulating air through the drying compartment in a direction from the foot portion to the top of the stockings.

21. A hosiery drier comprising a chamber, a drying compartment within the chamber, devices for supporting a plurality of boarded stockings within the drying compartment, a fan for circulating air through the drying compartment in a direction from the foot portion to the top of the stockings, and means converging the air current as it leaves the fan to cause it to strike directly against the heel and the toe portion of the stocking.

22. A hosiery drier comprising a chamber having a flat top arranged at a height convenient for the boarding of hosiery thereon, a plurality of drying compartments arranged in the upper portion of the chambers, doors leading to the drying compartments, a tray slidably mounted within each drying compartment for holding the boarded hosiery, and a common heating chamber extending beneath the drying compartments.

23. A hosiery drier comprising a chamber, a plurality of drying compartments arranged in the upper portion of the chamber, a heating compartment in the lower portion of the chamber, fans within the chamber at one end of the drying compartments, and direct connected fan motors located outside the chamber.

24. A hosiery drier comprising a chamber having a drying compartment therein and a stocking tray slidably mounted in the drying compartment, the stocking tray comprising a steel framework, guides at the forward end thereof for the reception of the boarded stockings between adjacent guides, and a combined heel and toe rest consisting of glass rods supported in fixed relation to one another and adjustably movable as a unit with relation to the frame of the tray.

25. A drying apparatus comprising a chamber, a drying compartment within the chamber, a heating compartment, means for circulating the air within the chamber from the heating compartment through the drying compartment, and thermostatically operated means for maintaining the temperature of the air thus circulated below the temperature at which injury to the material would occur.

26. A hosiery drier comprising a chamber, a plurality of separate drying compartments within the chamber, a fan for each drying compartment, means for heating the air circulated by the fans, and means for automatically maintaining the temperature within the chamber below 212 degrees F. to avoid injury to the hosiery.

27. A drying apparatus comprising a heat insulated chamber, means for supporting

material to be dried within the chamber, a fan for re-circulating the heated air over the material, and means for controlling the temperature of the air to maintain it below a predetermined limit.

70

28. A hosiery drier comprising a chamber, a drying compartment within the chamber, a heating compartment, means for maintaining the air within the chamber at a relatively low temperature, and mechanical means for delivering the air directly upon the stockings at a relatively high velocity.

75

29. A hosiery drier comprising a chamber, a plurality of separate drying compartments within the chamber, a door for each drying compartment, a heating compartment for heating the air within the chamber, means for circulating air through the heating compartment and through each drying compartment, and means for controlling the circulation through each compartment independently of the other compartments.

80

30. A hosiery drier comprising a chamber, a plurality of drying compartments in the chamber, a heating compartment in the chamber, and independently operating means for each compartment for circulating air therethrough.

85

31. A hosiery drier comprising a drying compartment, a tray within the compartment having a transverse support for the boarded stockings, said support being provided with vertical guides to separate the boarded stockings and with a strip of resilient material interwoven with the guides at the base thereof to cushion the boarded stockings.

90

32. A hosiery drier comprising a drying compartment, a tray for supporting the boarded stockings, a transverse support at one end of the tray for supporting the upper end of the boarded stockings, and a foot rest for supporting the foot end of the boarded stockings, the foot rest having upwardly opening slots on the inner faces thereof and bars removably supported in the slots.

95

33. A hosiery drier comprising a cabinet having a horizontal partition forming an upper drying compartment and a lower heating chamber, the partition being interrupted at its front and rear to form passages for the circulation of air, a fan for circulating the air, heating means in the heating chamber, a door in the drying compartment, and a tray for supporting the boarded hosiery with the longer axis horizontal and extending from front to rear and with the shorter axis vertical.

100

34. A hosiery drier comprising a cabinet having a plurality of separated drying compartments, means within the cabinet for heating the air, a fan for each compartment

105

110

115

120

125

130

- for continuously circulating the heated air therethrough and over the heating means, a steam supply for the heating means, and a single valve and thermostatic element for 5 controlling the temperature of the air being circulated through the several drying compartments.
35. A hosiery drier comprising a cabinet having a flat top at a height convenient for 10 boarding the hosiery, a plurality of drying compartments in the upper portion of the cabinet, means for heating the air in the lower portion of the cabinet, the drying compartments being relatively long and having 15 means for supporting the boarded hosiery with its longer axis horizontal and the shorter axis vertical, each compartment also having air passages at the front and rear thereof to permit the flow of air to and from the 20 compartments and from and to the heating means in a continuous circulation, a separate fan for circulating the air through each drying compartment and over the heating means arranged to deliver the heated air first onto 25 the foot portion of the boarded hosiery and thence toward the top, a separate motor for each fan, the motor being located outside the
- cabinet, and a separate door for each drying compartment.
36. A hosiery drier comprising a cabinet 30 having a horizontal partition forming an upper drying compartment and a lower heating chamber, the partition being interrupted at its front and rear to form front and rear passages for the circulation of air, 35 a fan for circulating the air, heating means in the heating chamber, a door in the drying compartment adjacent the front air passage and means movable into and out of the drying compartment when the door is open for 40 supporting the hosiery, said means when in position within the drying compartment overlying the front air passage and having its bottom open at its front end to permit the passage of air therethrough and through 45 the front air passage.
37. A hosiery drier comprising a cabinet, a drying compartment in the upper portion of the cabinet, a heating chamber in the lower portion of the cabinet, a fan within 50 the cabinet for circulating the air and a direct connected fan motor located outside the cabinet.

EARLE C. POWERS.
